UNITED STATES PATENT OFFICE

125,142

DESIGN FOR A RUG

Lucien Biva, Long Island City, N. Y., assignor to William E. Roschen, John Hastedt, and Albert
A. Levy as coexecutors of the estate of Otto
Timme, deceased

Application December 17, 1940, Serial No. 97,396

Term of patent 7 years

To all whom it may concern:

Be it known that I, Lucien Biva, a citizen of the United States, and a resident of the city of New York (Long Island City, Borough of Queens), county of Queens, and State of New York, have invented the new, original, and ornamental Design for a Rug, of which the following is a specification, reference being had to the accompanying drawing, forming part thereof.

The figure is a plan view of a rug embodying my design.

I claim:

The ornamental design for a rug, as shown.

LUCIEN BIVA.
